RUN AND TAP CONNECTOR

Joseph Sylvester, Erie, Pa., assignor to Penn-Union Electric Corporation, Erie, Pa., a corporation of Pennsylvania

Application March 23, 1959, Serial No. 55,142

Term of patent 14 years

(Cl. D26—1)

Fig. 1 is a perspective view showing one side of the run and tap connector embodying the design;

Fig. 2 is a perspective view showing the other side of the connector;

Fig. 3 is a side elevation of the connector;

Fig. 4 is an end elevation taken from the right end of Fig. 3; and

Fig. 5 is a plan view taken from above with reference to Fig. 3.

I claim:

The ornamental design for a run and tap connector, substantially as shown.
